[57] CLAIM

The ornamental design for a children's bed tent, as shown and described.

DESCRIPTION

FIG. 1 is a perspective view of the children's bed tent showing our new design;
FIG. 2 is a front elevational view thereof with the windows in the closed condition;
FIG. 3 is a rear elevational view thereof with the window in the closed condition;
FIG. 4 is a left side elevational view thereof with the window in the closed condition, the right side elevational view being a mirror image of the view shown in this figure;
FIG. 5 is a top plan view thereof; and,
FIG. 6 is a bottom plan view thereof.
